BEAN GRADER

Benjamin I. Buck, Baltimore, Md.

Application December 30, 1932, Serial No. 649,641

6 Claims. (Cl. 209—350)

This invention relates to improvements in machines for grading beans and particularly for sorting or grading, as to cross-sectional size, beans commonly known as string beans.

5 One object of the invention is to provide a grading machine of exceedingly simple construction.

Another object is to provide a machine having any desired number of what, for convenience, will be termed grading units, whereby beans may 10 be sorted into any desired number of grades.

A still further object is to provide a novel form of means for collecting the individual grades of beans as they are sorted or graded in the machine.

A further object is to provide a bean grading 15 machine wherein the beans being handled are substantially constantly agitated but in a manner whereby they cannot possibly be mashed, bruised or otherwise destroyed.

With these and other objects in view, the invention consists in certain details of construction and combinations and arrangements of parts, all as will hereinafter be more fully described and the novel features thereof particularly pointed out in the appended claims. A construction constituting the preferred embodiment of my invention is illustrated in the accompanying drawings, forming part of this specification, in which:

Figure 1 is a vertical sectional view of one form of apparatus embodying the preferred embodiment of the invention;

Fig. 2 is a horizontal sectional view on the line 2—2 of Fig. 1;

Fig. 3 is a similar view on the line 3—3 of Fig. 1;

Fig. 4 is a vertical sectional view on the line 35 4—4 of Fig. 2, illustrating the mode of discharging graded beans from one of the collecting troughs;

Fig. 5 is a perspective view of one of the sections of the collapsible bottom of a collecting trough;

Fig. 6 is a sectional view on the line 6—6 of 40 Fig. 1;

Fig. 7 illustrates portions of the several grading surfaces; and

Fig. 8 is a vertical sectional view taken at right angles to Fig. 1, illustrating the driving mechanism.

Generally, the present invention comprises a series of vertically spaced perforated surfaces, the perforations in the several surfaces being of different size, and means for separately collecting 50 from each surface the beans which are too large to pass through the perforations therein. The beans are fed to the uppermost surface, the beans which pass through the perforations in that surface being delivered to the next lower surface until the smallest of the beans reach the last surface of the

series. Means are also provided for agitating the beans at practically all times and especially while they are in contact with the several surfaces to facilitate passage of beans through the several sets of perforations.

5 In the specific embodiment of the invention illustrated in the accompanying drawings, there is a main supporting frame, comprising a plurality of rigid uprights or standards 10 and in the top of said frame there is an opening 11 through which the beans are fed from a chute 12. Below said feed opening there are a plurality of vertically spaced grading members in the form of perforated plates or surfaces, 13, 14, 15 and 16, preferably of conical cross section so that beans 10 falling thereon and incapable of passing through the perforations 17 will gradually move toward the peripheries of the plates, where they will be collected as hereinafter described. Preferably, but not necessarily, the perforations in the several 15 plates or surfaces are of different size, the uppermost plate having the largest perforations, while the smallest perforations are in the lowermost, as shown in Fig. 7, it being understood that beans are graded according to their cross-sectional size, and not length, so that the perforations need only vary in width. Beans passing through the perforations of all except the lowermost plate are directed toward the next lower plate by radially inwardly inclined surfaces in 20 the form of inverted cone-shaped members 18, whose bases are cut away to permit the beans to fall on the next lower perforated surface. There may be as many perforated plates as is desired, depending upon the number of grades into which 25 the beans are to be sorted. The beans passing through the perforations of all except the lowermost plate are directed toward the next lower plate by radially inwardly inclined surfaces in 30 the form of inverted cone-shaped members 18, whose bases are cut away to permit the beans to fall on the next lower perforated surface. There may be as many perforated plates as is desired, depending upon the number of grades into which 35 the beans are to be sorted. The beans passing through the perforations of all except the lowermost plate are received on a plate 19, similar to plates 13 to 16, except it is not perforated.

Better results are obtained if the beans are 40 agitated on the surfaces of the various plates. This is preferably accomplished, in the case of plates 13 to 16, by imparting a vibratory motion to said plates. In the present machine, the plates are mounted on a shaft 20, each plate 45 having a hub portion 21 with a cross pin 31, extending through the shaft, and each hub.

Shaft 20 is enclosed in a sleeve 22, and the shaft and sleeve are rotatable in bearings 23 by a gear 24, on a shaft 25, said gear meshing with a gear 26 fast on the sleeve. Fast and loose pulleys, 27, 28, are provided on shaft 25, power being delivered from a suitable source through the fast pulley. The cross pins 31 extend through slots in sleeve 22 and the shaft 20 is adapted to 50 55

be reciprocated in the sleeve by means of a lever 29 pivotally mounted on the frame base 39, one end of said lever engaging the lower end of the shaft and the other end of said lever being provided with a cam roller 32 which engages a cam surface 33 on the under face of gear 26. To further augment registration of beans with perforations in the plates, one or more wipers 34, suspended from cross members 35 in the frame, are adapted to retard the circular movement that is imparted to the mass of beans by the rotating plates, this retardation of the mass of beans tending to cause the individual beans to be turned lengthwise of the perforations. Cross members 35 may also be utilized as supports for the inverted conical surfaces 18.

As heretofore described, the beans that cannot pass through the perforations of any one plate move radially outward toward the periphery of that plate and are collected separately from all the remaining beans. Preferably, the means for collecting the beans from each plate consists of a revolving trough from which the beans are transferred to a chute which delivers them to a suitable receptacle or reservoir. Referring particularly to Figs. 1, 2 and 4, each trough comprises inner and outer side walls 36, 37, connected by cross bars 38, and the inner wall 36 is mounted on the arms 39 of a spider whose hub 40 is attached to sleeve 22. The bottom wall of the trough is composed of a multiplicity of sections 41 hinged or pivoted in the side walls 36, 37, the several sections being supported throughout the major portion of the travel around the perimeter of the plate by a way 42, mounted on brackets 43. At any desired number of points, however, the way is cut away, as shown in Fig. 4, and beneath each cut away portion there is a chute 44, the width and depth of the chute being such that one or more of the trough bottom sections 41 will turn on its pivot or drop, with the result that the beans supported thereon will fall into the chute. The end of the way with which the tripped sections come in contact as they move across the chute may be rounded or beveled as at 45, to facilitate restoring the sections to normal horizontal position on the way. One or more arms 39, of each spider also carries a wiper 46 which assists in moving the beans on the surfaces of the inverted conical surfaces 18.

In operating the apparatus, the beans are fed through hopper 12 on to the upper revolving surface 13. Those beans which are too large to pass through the perforations 17 in that plate, move down the inclined surface, radially outward from the shaft and sleeve carrying the plate and fall from the edge of the plate into the revolving trough, from whence they are deposited in the uppermost chute 44 as the sections of the trough bottom move across the chute when the way 42 is cut away.

The beans which pass through the perforations in plate 13 are received in the uppermost inverted conical member 18 whose radially inwardly sloping surface directs them onto the next lower perforated surface 14. The beans too large to pass through the perforations of this plate are received in the trough and delivered to the chute at the edge of said plate.

Beans passing through plate 14 are received on an inverted conical surface 18 and delivered to the next lower perforated surface 15 where the next grade of bean is segregated in like manner while the remaining beans passing through the perforations in said surface fall on another in-

verted conical member 18 and are delivered to the lowermost perforated plate 16. Here the next to the smallest beans are sorted out. Those beans which are so small that they will pass through the perforations of plate 16, fall on plate 19 and are delivered from the apparatus by the lowermost chute 44. As hereinbefore stated, there may be as many perforated plates as desired. 5

In addition to the perforated plates being revolved, they are also being reciprocated vertically during the entire operation, whereby the beans are constantly agitated. At the same time, the beans are also under the influence of the several wipers 34, 46. 10

What I claim is:

1. In a machine for grading beans, the combination of a vertically arranged series of perforated members, the perforations being graduated as to width with the larger perforations in the upper member and the smaller perforations in 20 the lower member, means for directing beans passing through the perforations in one member to the next lower member, an endless traveling trough movable around the perimeter of said means in which beans that cannot pass through 25 the perforations of a member are collected, said troughs having collapsible sectional bottoms for discharging beans therefrom, and means for agitating the beans on said members. 15

2. A machine for grading bean pods comprising the combination of a frame, a vertical shaft journaled therein, means for rotating said shaft, a series of frusto-conical plates secured to said shaft in spaced relation and each provided with a plurality of radial slots, a series of funnels 30 fixed in the frame between the respective plates of said series, each funnel having a central opening adjacent the upper central portion of the plate next beneath it, a plurality of annular troughs positioned to receive pods from the lower 35 edges of said plates, and means for revolving said troughs. 40

3. A machine for grading bean pods comprising the combination of a frame, a vertical sleeve journaled therein, means for rotating said sleeve, a vertical shaft within said sleeve, driving connections between the sleeve and shaft such as to permit a limited longitudinal movement of the shaft with respect to the sleeve, a series of frusto-conical plates mounted in spaced relation on the 50 sleeve and keyed to the shaft, each plate having a plurality of radial slots therein, a series of funnels fixed in the frame between the respective plates of said series, each funnel having a central opening adjacent the upper central portion of the 55 plate next beneath it, a series of spiders fixed to the sleeve, annular troughs carried by said spiders in position to receive pods from the lower edges of said plates, and means for reciprocating the shaft within the sleeve. 60

4. In a machine for grading beans, the combination of a vertically arranged series of perforated members, the perforations being graduated as to width with the larger perforations in the upper member and the smaller perforations in 65 the lower member, devices for directing beans passing through the perforations in one member to the next lower member, and an endless traveling trough movable around the perimeter of each of said devices in which beans that cannot pass through the perforations of a member are collected, said troughs having collapsible sectional bottoms for discharging beans therefrom. 70

5. In a machine for grading beans, the combination of a vertically arranged series of perfo- 75

rated members, the perforations being graduated as to width with the larger perforations in the upper member and the smaller perforations in the lower member, devices for directing beans passing through the perforations in one member to the next lower member, and an endless traveling trough movable around the perimeter of each of said devices in which beans that cannot pass through perforations of a member are collected, and means for discharging beans from said troughs at predetermined points thereof.

6. A machine for grading bean pods comprising the combination of a frame, a vertical sleeve journaled therein, means for rotating said sleeve, a vertical shaft within said sleeve, driving connections between the sleeve and shaft such as

to permit a limited longitudinal movement of the shaft with respect to the sleeve, a series of frustoconical plates mounted in spaced relation on the sleeve and keyed to the shaft, each plate having a plurality of radial slots therein, a series of funnels fixed in the frame between the respective plates of said series, each funnel having a central opening adjacent the upper central portion of the plate next beneath it, and an endless traveling trough movable around the perimeter of each funnel in which beans that cannot pass through the perforations of a member are collected, and means for reciprocating the shaft within the sleeve.
